UNITED STATES PATENT OFFICE.

JAMES H. GRAHAM AND EVERETT C. MURDICK, OF TORRINGTON, CONNECTICUT,
ASSIGNORS, BY MESNE ASSIGNMENTS, TO THE TORRINGTON COMPANY, OF
TORRINGTON, CONNECTICUT, A CORPORATION OF CONNECTICUT.

CARPET-SWEEPER.

1,384,997.

Specification of Letters Patent. Patented July 19, 1921.

Application filed June 5, 1917. Serial No. 172,879.

To all whom it may concern:

Be it known that we, JAMES H. GRAHAM and EVERETT C. MURDICK, citizens of the United States, residing at Torrington, in 5 the county of Litchfield, State of Connecticut, have invented certain new and useful Improvements in Carpet-Sweepers, of which the following is a description, reference being had to the accompanying drawing and 10 to the figures of reference marked thereon.

Our invention relates to improvements in carpet sweepers, and particularly to a novel arrangement for adjusting the brush by a single lever at the rear of the sweeper housing, that is, the end toward the operator, both ends of the brush being adjusted simultaneously and without interference with the freedom of its rotary action.

The invention, therefore, consists in the 20 matters hereinafter described and referred to in the appended claims.

The invention is illustrated in the accompanying drawings, in which:

Figure 1 is a longitudinal sectional view 25 of a sweeper embodying our invention;

Fig. 2 is a perspective view of the brush raising and lowering mechanism showing the several parts in their disassembled relation;

Fig. 3 is a perspective view of the sweeper showing the frame partly broken away and showing the brush raising and lowering mechanism; and Fig. 4 is a section showing the connection between the yoke parts.

Referring now to the drawings:

1 represents the frame or housing of our improved sweeper which is made of any desired material and provided at the center with the rotary sweeper brush 2, having its 40 trunnions 3 and 4 extending outwardly through vertical slots 5 and 6 in the end walls 7 and 8 of the housing. On each side of the brush are arranged the dust or dirt receptacles 9 and 10, all of which is well 45 understood and needs no further description. The front and rear walls 9' and 10' of the frame extend beyond the end walls 7 and 8, as clearly shown in Fig. 1 of the drawings.

The extreme outer ends of the walls are 50 connected together by the usual bars 11 and 12 which have their ends turned inwardly as indicated at 13 and secured to the walls, thus forming a space 14 between the bars and the end walls 7 and 8 of the housing. 55 Mounted on trunnions 16 carried by the end

walls 7 and 8 are the supporting and drive wheels 17, which as shown, are four in number, two at each end of the frame, and arranged at all times to engage the friction wheels or rollers 18 carried by the ends of 60 the trunnions 3 and 4 of the brush 2.

Pivots 19 and 20 are provided at the inner faces of the bars 11 and 12 to support the yoke 21 which extends forwardly to the front of the housing and passes inwardly into the 65 same through openings 22 in the end walls 7 and 8. The free ends of the yoke beyond the pivots 19 and 20 are provided with elongated slots 23 which are arranged opposite the center of the drive rollers 18 carried by 70 the brush 2. The bars 11 and 12 have pivoted thereto at 24 the spring arms 25 which have their outer ends provided with rigid pins 26 which extend through the elongated vertical slots 23' in the bars 11 and 12 and 75 also through the elongated horizontal slots 23 in the yoke and enter the sockets 27 in the outer faces of the drive rollers 18 and form bearings for the brush as will be seen in Fig. 1 of the drawings. The spring arms 80 25 beyond the pins are struck out, as indicated at 28, so that the same can be grasped for the purpose of springing the arm outwardly so that the brush can be readily removed.

The yoke 21, as shown, is made of bar metal in two sections 29 and 30 and interlocked together by the tongues 31 and 32 and slots 33 and 34, as clearly shown in Figs. 2 and 3 of the drawings, which allows for 85 a certain amount of longitudinal movement or adjustment of the two sections in respect to each other. This connection between the two sections forming the yoke, also allows of the ready assembling of the yoke or removal of the same. The sections 29 and 30 are struck out as indicated at 35 to strengthen the same at a point where it is subjected to the greatest strain.

The front wall 9' of the housing has secured to its outer face a plate 36 to which is pivotally connected at 37 the L-shaped lever 38. The upper end of the lever is provided with a hand portion 39 whereby it can be operated. The lever below the hand portion is provided with portion 40 struck outwardly and forming a recess adapted to engage the serrated portion 41 of the upper end of the plate 36 whereby the lever may be held in its adjusted position. The outer 110

lower free end of the lever 38 is provided with a rigid inwardly extending pin 42 which passes through a segmental vertical slot 43 in the plate 36 and enters the registering elongated horizontal slots 44 and 45 in the two overlapping portions of the sections 29 and 30 forming the yoke.

The operation of the machine is as follows:—

10 The housing is supported by the wheels in the usual manner and is drawn back and forth over the carpet or floor to be swept by means of the handle 46. The wheels engaging the friction rollers 18, rotate the brush, all of which is the usual operation. It is often necessary or desirous to have a less or greater pressure of the brush on the surface to be swept and by moving the lever 38 to the right the lateral end carrying the 15 pin 42 is raised. This raises the yoke upwardly and rocks the free ends of the pivots 19 and 20 thus throwing the pins 26 downwardly, which in turn, lower the brush equally at both ends so that a greater pressure thereof on the surface being swept is obtained. This adjustment may also compensate for the wear of the bristles of the brush so as to insure the engagement of the brush with the sweeping surface. The 20 movement of the lever in the opposite direction raises the free ends of the yoke carrying with it the brush and thus decreases the pressure thereof on the surface being swept. The arms 25 being pivoted concentric with the supporting wheels, it will be seen that the movement of the roller of the brush is such that it will always engage the wheel and cause rotation of the brush.

Having thus described our invention, 40 what we claim as new and desire to secure by Letters Patent, is:—

1. A carpet sweeper comprising a housing having supporting means journaled therein, bars supported outside of and at the 45 ends of said housing, a bail pivoted to said bars and projecting into said housing, a rotatable brush shaft passing through said housing ends and detachably carried by said bail outside of said housing, and means located within said housing for adjusting said bail to raise or lower said brush shaft.

2. A carpet sweeper comprising a housing, bars extending across the ends of the frame and spaced therefrom, supporting wheels 55 carried by the housing within the said spaces, a yoke pivoted to the inner faces of the bars and extending within the housing, means in the housing for adjusting the yoke, a brush within the housing, rollers carried by the brush on the outside of the housing and engaging the supporting wheels, and means without the housing for removably securing the brush to the yoke.

3. A carpet sweeper comprising a housing, 60 bars extending across the ends of the frame

and spaced therefrom, supporting wheels carried by the housing within said spaces, a yoke intermediately pivoted to the inner faces of the bars and extending within the housing, means carried by the housing 70 for adjusting the yoke, a brush within the housing, rollers carried by the brush on the outside of the housing and engaging the supporting wheels, and pins carried by the bars and extending through slots therein 75 and through slots in the ends of the yoke and entering recesses in the ends of the friction rollers carried by the brush, whereby the brush is vertically adjustably supported and removable.

4. A carpet sweeper comprising a housing, bars extending across the ends of the frame and spaced therefrom, supporting wheels carried by the housing within the said spaces, a yoke pivoted to the inner faces of 85 the bar and extending within the housing, means within the housing for adjusting the yoke, a brush within the housing, rollers carried by the brush on the outside of the housing and engaging the supporting 90 wheels, a pivoted member carried by the bars and having pins extending through slots therein and through slots in the ends of the yoke and entering recesses in the 95 ends of the friction rollers carried by the brush whereby the brush is vertically adjustably supported and removable.

5. A carpet sweeper, comprising a housing, bars extending across the ends of the housing and spaced therefrom, supporting 100 wheels carried by the housing within the spaces, a yoke formed of two sections having interlocking slots and tongues and pivoted to the inner faces of the bars and extending into the housing and across the 105 front thereof, a plate carried by the housing, an L-shaped lever carried by the housing, means for holding one end of the lever in its adjusted position, a pin carried by the opposite end of the lever and passing through 110 a slot in the plate and entering slots in the overlapping portions of the yoke sections, a brush within the housing, rollers carried by the brush on the outside of the housing and engaging the supporting wheels, and pivoted spring members carried by the bars 115 and having pins extending through slots therein and through slots in the ends of the yoke and entering recesses in the ends of the friction rollers carried by the brush 120 whereby the brush is vertically adjustably supported and removable.

In testimony whereof, we affix our signatures in the presence of two witnesses.
